UNITED STATES PATENT OFFICE.

GEORGE W. RAMSEY, OF PEORIA, ILLINOIS.

TABULATING MECHANISM.

1,109,870.

Specification of Letters Patent. Patented Sept. 8, 1914

Application filed October 5, 1910. Serial No. 585,370.

To all whom it may concern:

Be it known that I, GEORGE W. RAMSEY, a resident of Peoria, in the county of Peoria, State of Illinois, (whose post-office address is Provident Bank Building, Washington, District of Columbia,) have invented certain new and useful Improvements in Tabulating Mechanism, of which the following is a specification.

10 This invention relates broadly to the arts of typewriting machines, adding machines and any type of printing machine using a carriage which moves past the printing point or a carriage wherein the printing point is moved over the printing surface.

The invention relates more specifically to tabulating mechanisms adapted particularly for the above mentioned type of machines.

20 The principal object of this invention is to provide a tabulating mechanism wherein certain stop members are automatically set during a printing operation.

25 More specifically the object of this invention is to set certain tabulating stops during a printing operation and after a certain pre-determined operation has been performed.

30 Another object of this invention is to construct a tabulating mechanism wherein certain tabulator stops are automatically set when printing keys are operated in a pre-determined sequence.

35 A further object of this invention is to construct a tabulating mechanism for typewriting machines wherein certain carriage stops are set when a pre-determined punctuation key has been struck after a predetermined character key.

40 A still further object of this invention is to construct a tabulating mechanism where- 45 in carriage determining stops are automatically set when a period key is struck immediately after a numeral key.

45 Other and further objects of this invention will in part be obvious and will in part be more specifically pointed out in the specification hereinafter, by reference to the accompanying drawings, and the scope of the invention will be indicated by the claims.

50 Throughout the several figures of the drawings, like numerals will be used to indicate like parts.

55 Figure 1 is a view of a typewriting machine in elevation, with certain parts thereof omitted, showing the carriage stop bar in section. Fig. 2 is a detail elevational view showing the mechanisms for automatically setting the carriage stops. Fig. 3 is a detail plan view showing the relationship of certain of the tabulating mechanisms. Fig. 4 is a view showing portions of the carriage stop rack in section. Fig. 5 is an end view of the carriage stop rack. Fig. 6 is a detail view of one end of the carriage stop rack. Fig. 7 is a detail view of the carriage stop actuator. Fig. 8 is a view showing a part of the setting bar in its relation to the key lever. Fig. 9 is a view showing a part of the releasing bar in its relation to the key lever.

setting the carriage stops. Fig. 3 is a detail plan view showing the relationship of certain of the tabulating mechanisms. Fig. 4 is a view showing portions of the carriage stop rack in section. Fig. 5 is an end view of the carriage stop rack. Fig. 6 is a detail view of one end of the carriage stop rack. Fig. 7 is a detail view of the carriage stop actuator. Fig. 8 is a view showing a part of the setting bar in its relation to the key lever. Fig. 9 is a view showing a part of the releasing bar in its relation to the key lever.

It is believed that the principal novelty of the invention illustrated in the drawings, and which will be more specifically described hereinafter, resides in the method of setting certain tabulator stops when certain pre-determined operations have been performed. The particular mechanical adaptation of this invention is illustrated and will be described as applied to a type of typewriting machines commonly known as the Monarch typewriter, however, that particular type of machine has been selected for the purpose of illustrating the invention, and not as a limitation for its adaptation, for the reason that it is equally well adapted to all different types of machines using a movable carriage.

As the denominational stops, which are adapted to coöperate with the carriage stops, do not form a specific part of this invention, the denominational stop mechanism has not been illustrated in its entirety, but for the purpose of illustration I have chosen to adopt the type of denominational stop which is specifically shown and described in the patent to Felbel, Serial No. 904,689, patented November 24, 1908. However, any other well known type of denominational stop mechanism might with equal efficiency be used in connection with the mechanism for automatically setting the carriage stops.

Furthermore, the particular mechanism herein illustrated shows the automatic stop setting mechanism as being operative upon a series of stops carried on the movable carriage. It is equally well known and considered as equivalents in the art, to arrange column selector stops on a bar mounted on the fixed frame of the machine and to arrange the denominational stops such that they are carried by the movable carriage. Therefore, I desire that it shall be understood that the mechanism for automatically setting

stops can be arranged to work with equal facility in connection with column stops carried upon a bar mounted on the frame work of the machine and arranged to coöperate with any well known type of denominational stops carried by a movable carriage.

Referring to the drawings and more particularly to Fig. 1 of the drawings, a machine frame 1 is adapted to support a top plate 2, upon which are mounted brackets 5, only one of which is shown in Fig. 1, which are adapted to carry between their upper ends a top rail 6 and at their base a bottom rail 7, both of which rails are grooved in order to form run-ways for balls 8, which form anti-friction bearings adapted to carry a carriage frame 9. The carriage frame 9 includes side plates 10 and 11, which are adapted to support upon their forward ends a cylindrical platen 12. A spring drum 14, is mounted in the machine frame and is attached to a post 15, mounted on the carriage frame, by means of a tape 16, in order that the carriage may be moved for letter spacing. An escapement wheel 17, is mounted in a bracket 18, and is operatively connected by means of a shaft running through the bracket, to a small cog wheel 19, with which a rack 20 is adapted to coöperate in order to control the movement of the carriage. The rack 20 is mounted upon the well known releasing mechanism carried by the carriage and which terminates in a releasing lever 21. An escapement lever 22, which carries escapement dogs that are adapted to coöperate with the escapement wheel 17, is supported upon a bracket 24, which depends from the top plate 2. One portion of the escapement lever 22 is connected with a universal bar mechanism 25, by means of a link 26. The universal bar mechanism 25, is mounted in the machine frame in a manner well known in the art, beneath printing keys 27, which are pivoted upon a rod 28 that is mounted in the machine frame, and terminate at their forward ends in key caps 29. Key lever springs 30, are arranged in such manner as to cause the key levers to be returned to normal position after they have been depressed. Type bars 31, are mounted in a type bar segment 32. Sub-levers 34 are pivotally mounted upon the key levers 27, and are connected to the type bars 32 by means of links 35. The sub-levers 34 coöperate with a rod or abutment 36, in such manner as to be effective to operate the type bar when the printing key lever is depressed. Denominational stop keys 37, are mounted upon a bracket or web member 38, and terminate at their forward ends in key caps 39, which are substantially above and to the rear of the ordinary typewriter key board. I have only illustrated one of the denominational stop keys, but it is to be understood that a requisite number of denominational

stop keys together with connecting links and attendant mechanisms, are to be used sufficient to operate the usual number of denominational stops. Denominational tabulating stop carriers 40, are mounted on the machine frame 1, in a bracket 41, and are connected with the denominational stop keys 37, by means of connecting links 42. The denominational stop carriers 40, terminate at their upper ends in denominational stops 44, the construction and arrangement of parts being such that when a certain denominational stop key is depressed, a corresponding denominational stop will be moved forward sufficiently to be in the path of column stops 48 or carriage stops which may be set, as will be more fully described hereinafter. The side plates 10 and 11 of the carriage frame, are continued to the rear at their upper ends, and carry a stop rack 45, which is composed of a top plate 46 and a lower plate 47. The plates 46 and 47 are formed with recesses in which carriage or column stops 48 are adapted to be slidingly mounted. Each of the carriage stops 48 consists of a stop face 49 which is beveled at its rear, a top spring bar 50 and a lower slide bar 51, which is provided with a lug 52, for a purpose which will be hereinafter described. The top spring bar 50 is provided with two locking notches 54 and 55. A locking bar 56, depends through a longitudinal opening in the top plate 46, and is supported by means of bell crank levers 57 and 58, which are pivotally mounted upon the ends of the top plate 46. Leaf spring members 59, are mounted in the top plate and are adapted to seat the locking bar 56 in the notches 54 and 55 of the carriage stops. A retractor bar 60 passes through openings formed in the side plates 10 and 11, and is connected at its ends with the bell crank levers 57 and 58 respectively, by means of slotted openings formed in the bell cranks. Link members 61, extend from each end of the retractor bar 60 to levers 62, which are mounted in the side plates 10 and 11, upon a shaft 64, which so connects the lever 62 that the links 61 will be uniformly drawn forward when either of the levers are operated.

Referring more particularly to Figs. 2, 3, 7, 8 and 9, a bracket member 65, is fixedly mounted upon the machine frame 1 approximately beneath the printing key 27, which is adapted to actuate the type bar 31 carrying thereupon the period (.) punctuation mark. A setting bar 66, is fixedly mounted upon a bell crank member 67, which is pivotally mounted on a shaft 68 supported in the machine frame and by means of the bracket 65. The setting bar 66 is provided on its upper surface with raised abutments 69, which are adapted to be positioned directly beneath each particular printing key 27 that is adapted to actu-

ate any type bar carrying thereupon a numeral. In typewriting machines in which the character capital O is adapted to be used for printing the cipher, the abutment 69 is also positioned beneath the particular printing key 27 which actuates the type bar carrying the character capital O thereupon. A retractor spring 70, is attached to the bracket 65 and to the bell 10 crank member 67, and normally holds the bell crank member against a stop pin 71, that is mounted on the bracket 65. The upper end of the bell crank member 67 is formed into a latch 72, which is provided 15 with a hook member 74. The upper end of the bell crank member is also provided with a locking notch 75. A releasing bar 76, is carried upon an arm 77, which is also mounted upon the shaft 68, and which is 20 connected to a locking dog 78 by means of a link member 79. The locking dog 78 is pivotally mounted in a bracket 80 that depends from the machine frame 1, and a leaf spring 81 also mounted upon the machine 25 frame 1, is adapted to normally force an engaging head 82 of the locking dog into contact with the upper end of the bell crank 67. The releasing bar 76, is provided with notches 84, which are located in the same 30 relation to the key levers as are the raised abutments 69. In other words, the releasing bar 76 is provided with a notch that corresponds, with reference to each key lever, to the abutments 69 that are formed on 35 the setting bar 66. The releasing bar 76 is normally a sufficient distance beneath the key levers to be entirely out of their zone of movement. The abutments 69 on the setting bar 66, are sufficiently high so that 40 the bar will not be actuated by any key other than the particular keys directly above the abutments, and the notches in the releasing bar 67, are sufficiently deep that the releasing bar will not be actuated by 45 the depression of any numeral key.

Referring more particularly to Figs. 2, 3 and 7, a shaft 85 is mounted in brackets 86 and 87, upon the top rail 6. A crank member 88 is fixedly mounted upon the shaft 85 50 at a position directly above the printing key adapted to print a period. A supplemental lever 89 is pivotally mounted upon a printing key adapted to actuate the type bar carrying thereon a period. The supplemental lever 89 is provided with a forwardly extending hook 90, and on its extreme rear end with a locking hook 91. A link 92, is connected to the crank member 88, and is provided on its lower end with a 55 head 94 in which there is an opening which is adapted to engage the forwardly extending hook 90 attached to the supplemental lever 89. The link 92 is adapted to pass through a dis-connecting rod 95, which terminates at its forward end in a key cap 96,

and at its rear end is slidably mounted in a bracket 97, that is attached to the machine frame 1. The upper rear portion of the dis-connecting rod 95, is provided with retaining notches 98 and 99, and is held in contact 70 with the under face of the bracket 97 by means of a small leaf spring 99 that is mounted on the machine frame 1. It will be noted that a longitudinal movement of the dis-connecting rod 95, will either connect 75 or dis-connect the supplemental lever 89 with the crank member 88, thus enabling the operator to determine when the automatic column stop setting mechanism shall be operative.

Referring particularly to Figs 3 and 7, an actuating dog 100, is slidably mounted upon a squared portion of the shaft 85 at a position which is directly to the rear at which the type heads are adapted to strike 85 the platen. A light coiled spring 101, normally maintains the actuating dog in contact with the bracket 86, and by its torsional effort also normally maintains the actuating dog retracted, against a stop 90 plate 102.

In the majority of tabulating work the starting, or base point, of the tabulating is usually determined by the decimal point or period. Therefore, it will be noted that if 95 the dis-connecting key be pushed in thus connecting the supplemental lever with the stop setting mechanism, a column stop or carriage stop will be automatically positioned or set each time a period or decimal point is struck immediately after the printing of a figure or numeral. The manner in 100 which this operation is performed will be more specifically described by designating the operation of the hereinbefore specified 105 mechanism.

Referring particularly to Figs. 2, 3, 8 and 9, and presuming that the dis-connecting key has been pushed in in order that the supplemental lever 89 is connected with the 110 crank member 88, it will be noted that if a numeral printing key 27 be depressed it will contact with one of the abutments 69 on the setting bar 66, thus rocking the bell crank 67 and permitting the engaging head 82 of the locking dog 78 to drop into the locking notch 75, thus positioning the latch 72 over the supplemental lever 89, at the same time raising the releasing bar 76 into operative position beneath the several letter keys. 115 The parts will be held in this locked position so long as numeral keys are operated, but if a letter key be depressed it will contact with the face of the releasing bar 76, which will be depressed, and will lift the 120 engaging head 82 from the locking notch 75, thus permitting the retractor spring 70 to withdraw the latch 72 from its position over the end of the supplemental lever. The supplemental lever therefore being free at 125 130

its rear end and being pivoted at its forward end, will rock upon its pivot without actuating the automatic stop setting mechanism. As long as numeral keys are depressed however, the parts will be held in locked relationship, for the reason that the numeral keys will pass downward into the notches 84 of the releasing bar without actuating the bar, and therefore the several parts will be held in locked position. If while in locked position the period key is depressed, the supplemental lever 89 will be carried downward with this key, for the reason that the rear end thereof cannot rise because of the latch 72. However, the period key will contact with the releasing bar, thus lifting the engaging head 82 of the locking dog 78 from the locking notch 75, and will permit the latch 72 to be retracted sufficiently to allow the engaging head 82 to ride over the top of the latch 72, and until the hook member 74 engages the locking hook 91 on the supplemental lever, which will prevent a further retraction of the latch 72 until finger pressure is released upon the period key. Immediately as finger pressure is removed from the period key, the hook member 74 and the locking hook 91 will be disengaged and the parts will return to normal position.

Referring particularly to Figs. 1, 2, 3 and 7, it will be noted that when the shaft 85 is rocked, the actuating dog 100 engages with a column or carriage stop and slides it outward in the stop rack 45, lifting the locking bar 86 and permitting it to drop into the locking notch 55, as is indicated in Fig. 5. Thus it will be seen that a column or carriage stop is automatically positioned each time a period printing key is actuated immediately after the actuation of a numeral key.

It might be possible in the rapid operation of the machine that the actuating dog 100 when setting a tabulator stop, would not be retracted quick enough from the stop rack to prevent contact with the side of the succeeding stop, and therefore the actuating dog is arranged to slide upon the shaft 85 against the pressure of the light coiled spring 101, in order to prevent any retarding of the carriage under letter space movement. Immediately of course as the actuating dog 100 leaves the rack it will be returned to normal position against the bracket 86 by means of the light coiled spring 101.

Referring particularly to Figs. 1, 4, 5 and 6, it will be noted that when it is desirable to retract the set carriage or column stops, it is only necessary to draw forward on one of the levers 62. This movement draws the links 64 forward, thus rocking the bell cranks 57 and 58 to lift the locking bar 56 from engagement with the locking notches 55. Simultaneously the retractor bar is

drawn against the lugs 52, and the stops 48 which have been positioned, are withdrawn to normal position. It will also be noted that the space between the retractor bar and the lugs 52 is sufficient to permit the locking bar 56 to be disengaged from the notches 55 before the retractor bar engages the lugs 52.

As has been hereinbefore stated, this device is adapted to set carriage or column stops automatically during the printing operation. For special work it may be desirable to have the tabulating stops set after characters other than numerals and during the printing operation of a character other than a decimal point or period. In such case it is only necessary to vary the setting bar 66 and the releasing bar 76 in accordance with the particular requirement. Of course in such case it will be necessary to arrange the supplemental lever 89 and attendant mechanisms over the proper printing key.

In tabulating work it may be desirable at times to manually set the column stops without printing the period or without the necessary operation of depressing the period key. When such a condition arises it is only necessary that the disconnecting rod 95 be drawn forward to disconnect the link 92 from the sub-lever 89, in a manner which has hereinbefore been described. When these parts are disconnected tabulating stops may be set manually by moving the carriage 9 and the stop carrying rack 45, which of course will move with the carriage since it is attached thereto, in such manner that the stop desired to be set is exactly back of the printing point, and then utilizing the crank arm 88 as a finger piece. When the crank arm 88 is depressed by finger pressure thereupon, the shaft 85 will be rocked and the actuator 100 will set one of the tabulating stops 48 in a manner which has hereinbefore been described. Therefore it will be seen that this device is of such a character that tabulating stops may be set manually as well as automatically.

From the hereinbefore described mechanism it will be noted that the automatic stop setting mechanism is specifically described as being attached to the printing key which is adapted to actuate the type bar carrying thereupon the period character. Necessarily the automatic stop setting mechanism will require a certain amount of energy to operate the same. This excess pressure is a desirable rather than an undesirable factor, for the reason that the face of the period key being so small the usual amount of key pressure will throw the period key so forcibly against the platen and paper as to puncture the paper and make a smudged or undesirable imprint. In order to avoid perforation of the paper many commercial typewriting machines are arranged in such manner that it requires

more force to operate the period key than to operate a letter key. It will be seen that the automatic stop setting mechanism disclosed in this application will perform the function of utilizing a portion of the finger key pressure necessary to operate the period key, and therefore it will tend to prevent the period from perforating the paper and at the same time will tend to balance or even the touch over the key board in such manner that the operator will not be required to strike the period key with less force than a letter key, as is the usual condition wherein the period key is not provided with a braking mechanism.

This invention is believed to be broadly new, and therefore as many changes could be made in the above construction and the manner in which the same is carried out, and many widely different embodiments of the mechanism could be utilized without departing from the scope of the invention, I intend that all matter contained in the above described structure and shown in the accompanying drawings shall be interpreted as illustrative and not in a limiting sense.

Having thus described my invention what I desire to claim is:—

1. A device of the character described including a frame, a movable carriage mounted on said frame, type bars, keys operatively connected with said type bars, a stop member operatively mounted on said frame, a series of stops carried by said movable carriage, and means operative by certain of said keys for positioning certain stops in said series of stops.

2. A device of the character described including a frame, a power propelled carriage mounted on said frame, type bars, keys operatively connected with said type bars, a movable stop member mounted upon said frame, a series of stops mounted upon said carriage, and means for automatically positioning certain stops in said series of stops when certain of said keys are actuated.

3. A device of the character described including a frame, a movable carriage mounted on said frame, letter spacing mechanism, keys adapted to operate said letter spacing mechanism, a series of stop members mounted on said movable carriage, and means operated by certain of said keys for positioning certain of said stops in said series.

4. A device of the character described including a frame, a movable carriage mounted on said frame, printing members, keys for operating said printing members, a series of denominational stop members operatively mounted on said frame, a series of movable stops operatively connected with said carriage, means operated by certain of said keys for positioning certain stops in said series of stops, and means for operating said denominational stops.

5. A device of the character described including a frame, a movable carriage mounted on said frame, a letter spacing mechanism, keys for operating said letter spacing mechanism, a series of denominational stops operatively mounted on said frame, a stop carrying rack mounted on said movable carriage, stops carried by said stop carrying rack, means for positioning certain of said stops carried by said rack when certain of said keys are operated, and means for positioning said denominational stops.

6. A device of the character described including a frame, a movable carriage, a stop member operatively connected with said movable carriage, a stop member operatively connected with said frame, printing members, keys operatively connected with said printing members, automatic means controlled by certain of said keys for positioning one of said stop members, and means for positioning the other of said stop members in the path of said automatically positioned stop.

7. A device of the character described including a frame, a power propelled carriage, letter spacing mechanism, keys adapted to operate said letter spacing mechanism, stop members operatively connected with said power propelled carriage, a stop member operatively mounted upon said frame, means operated by one of said keys for positioning certain of said stops carried by said carriage, and means for positioning the stop member on said frame in the path of the positioned stop members carried by the carriage.

8. A device of the character described including a frame, type members, keys for operating said type members, a movable carriage, a series of column stop members normally in inoperative position, a series of denominational stop members, means controlled by certain of said keys for automatically positioning certain of said column stop members, and means for positioning certain of said denominational stop members in such manner as to be in the path of the positioned column stop members.

9. A device of the character described including a frame, type members, keys operatively connected with said type members, a movable carriage, a series of column stop members operatively connected with said carriage and normally in inoperative position, a series of denominational stops operatively mounted upon said frame, means in operative connection with certain of said keys for automatically positioning certain of said column stops, and means for positioning certain of said denominational stops in the path of the positioned column stops.

10. A device of the character described including a frame, type members, keys operatively connected with said type members, a

movable carriage mounted on said frame, a stop carrying rack operatively connected with said movable carriage, movable column stops mounted in said rack, denominational stops mounted upon said frame, means operated by certain of said keys for moving in said rack certain of said column stops from inoperative to operative position, and means for positioning certain of said denominational stops in the path of said operative column stops.

11. A device of the character described including a frame, type members, keys mounted in said frame and operatively connected with said type members, a movable carriage, a stop member operatively connected with said movable carriage and moving simultaneously therewith, a stop member mounted on said machine frame, means operatively connected with certain of said keys and adapted to set one of said stops in operative position when certain of said keys have been depressed in a predetermined sequence, and means for positioning the other of said stops in the path of the stop which was automatically set.

12. A device of the character described including a frame, type members, keys mounted in said frame and operatively connected with said type members, a movable carriage, a series of stop members operatively connected with said movable carriage and moving simultaneously therewith, a series of stop members mounted upon said machine frame, means operatively connected with one of said keys and adapted to set certain of said first mentioned stops when certain of said keys have been operated in a predetermined sequence, and means for positioning certain of said stops carried by the machine frame in the path of the automatically positioned stops.

13. A device of the class described including a frame, type actuating keys operatively mounted in said frame, a movable carriage, a stop carrying rack operatively connected with said carriage and moving simultaneously therewith, column stops movably mounted in said stop carrying rack, denominational stops mounted upon said machine frame, means operatively connected with one of said keys adapted to set certain of said column stops in operative position when certain of said keys have been depressed in a pre-determined sequence, and means for positioning certain of said denominational stops in the path of said column stops.

14. A device of the class described including a frame, type actuating keys operatively mounted in said frame, a movable carriage, a stop carrying rack, a series of column stops mounted in said stop carrying rack and normally in inoperative position, a series of denominational stops normally in inoperative position, means operatively con-

nected with one of said keys adapted to set certain of said column stops in operative position when certain of said keys have been depressed in a pre-determined sequence, means for positioning certain of said denominational stops in operative position in the path of said column stops, and means for releasing the carriage to permit said stops to contact.

15. A device of the class described including a frame, type actuating keys operatively mounted on said frame, a movable carriage, stop members operatively connected with said movable carriage and moving simultaneously therewith, stop members mounted upon said machine frame, means operatively connected with one of said keys adapted to set certain of said stops in operative position when certain of said keys have been depressed in a pre-determined sequence, means for operatively positioning stops in the path of said first mentioned stops, and means for releasing the carriage to permit said stops to contact.

16. A device of the class described including a frame, a movable carriage mounted upon said frame, printing means, finger keys operatively connected with said printing means, a stop carried by said movable carriage, a stop mounted upon said machine frame, means operatively connected with certain of said finger keys for automatically setting one of said stops when said finger keys have been operated in a predetermined sequence, and means for positioning the other of said stops in the path of said first mentioned stop.

17. A device of the class described including a frame, a movable carriage mounted upon said frame, printing means, finger keys operatively connected with said printing means, a stop carrying member operatively connected with said movable carriage, stops carried by said stop carrying member, stops mounted upon said machine frame, means operatively connected with one of said finger keys for automatically setting certain of said stops on said stop carrying member in operative position when certain of said keys have been operated in a pre-determined sequence, and means for positioning certain of said stops on said machine frame in the path of the operative stops carried by the carriage.

18. A device of the class described including a frame, a movable carriage mounted upon said frame, printing means, finger keys operatively connected with said printing means, a stop carrying rack operatively connected with said movable carriage, stops slidingly mounted in said stop carrying rack, a stop mounted on said machine frame, and means operatively connected with one of said finger keys for automatically setting certain of said stops carried by said rack in

the path of said stop mounted on said machine frame when certain of said keys have been depressed in a pre-determined sequence.

19. A device of the class described including a frame, a movable carriage mounted on said frame, printing means, finger keys operatively connected with said printing means, a stop carrying rack operatively connected with said movable carriage, a series 10 of column stops mounted in said rack normally in inoperative position, a series of denominational stops mounted upon said machine frame, means operatively connected with one of said finger keys for automatically 15 positioning certain of said denominational stops in operative position when said finger keys have been depressed in a pre-determined sequence, and means for positioning certain of said denominational stops 20 in the path of said operative column stops.

20. A device of the class described including a frame, a movable carriage mounted upon said frame, printing means, finger keys operatively connected with said printing 25 means, a stop carrying rack, a series of column stops mounted in said stop carrying rack and normally in inoperative position, a series of denominational stops normally in inoperative position, means operatively connected 30 with certain of said finger keys for automatically setting certain of said column stops in operative position when said finger keys have been operated in a pre-determined sequence, means for positioning certain of 35 said denominational stops in operative position in the path of said operative column stops, and means for releasing said carriage to permit said column and denominational stops to contact.

40 21. A device of the class described including a frame, a carriage movably mounted upon said frame, a stop carried by said carriage, a stop operatively mounted upon said frame, printing mechanisms, key levers operatively connected with said printing mechanisms, means for automatically setting one 45 of said stops when a punctuation key is operated immediately after a numeral key, and means for positioning the other stop in the 50 path of said first mentioned stop.

22. A device of the class described including a frame, a carriage movably mounted upon said frame, a stop carrier operatively connected with said carriage, stops mounted upon said stop carrier, printing mechanism, key levers operatively connected with said printing mechanism, a stop mounted on said frame, means for automatically rendering certain of said stops connected with said carriage operative to be engaged by said stop mounted on said machine frame when a punctuation key is operated in immediate sequence after a numeral key.

65 23. A device of the class described including a frame, a carriage movably mounted

upon said frame, a stop carrying rack operatively connected with said carriage and adapted to move simultaneously therewith, stops mounted upon said rack, printing mechanisms, key levers operatively connected with said printing mechanisms, stops mounted upon said frame, means for automatically setting certain of said stops on said stop carrier in operative position when a punctuation key is operated in immediate 70 sequence after a numeral key, and means for positioning certain of said stops mounted on said frame in the path of said operative stops carried by said rack.

24. A device of the class described including a frame, a carriage movably mounted upon said frame, a stop carrying rack, a series of column stops movably mounted in said stop carrying rack, printing mechanisms, key levers operatively connected with 80 said printing mechanisms, a series of denominational stops, means for automatically setting certain of said column stops when a punctuation key is operated in immediate 90 sequence after a numeral key, and means for positioning certain of said denominational stops in the path of the column stops which have been automatically set.

25. A device of the class described including a frame, a carriage movably mounted upon said frame, a stop carrying rack mounted upon said carriage, a series of column stops mounted on said rack, printing mechanisms, key levers operatively connected with said printing mechanisms, denominational stops mounted on said frame, means for automatically setting certain of said column stops when a punctuation key is operated in immediate sequence after a numeral key, and means for positioning certain of 95 said denominational stops in the path of said operative column stops.

26. A typewriting machine including a movable carriage, printing mechanisms, finger keys operatively connected with said printing mechanisms, a tabulating device including column stops, denominational stops, and means for automatically setting certain of said column stops when certain of said finger keys are operated in a predetermined 110 sequence.

27. A device of the class described including a frame; a movable carriage mounted on said frame; a stop carrying member operatively connected with said movable carriage; a stop member operatively connected with said frame; key levers; automatic means for positioning certain of said stops; said automatic means including mechanisms for rendering said automatic means operative when 115 certain of said keys are depressed, and means for rendering said automatic mechanisms inoperative when certain other of said keys are depressed.

28. A device of the class described includ-

ing a frame; a movable carriage mounted on said frame; a stop carrying member operatively connected with said movable carriage; stops carried by said stop carrying member; key levers; automatic means for positioning certain of said stop members; said automatic means including mechanisms adapted to be set and locked in position to render said automatic means operative when 10 certain of said printing keys are depressed.

29. A device of the class described including a frame, a movable carriage mounted on said frame, a stop carrying member operatively connected with said movable carriage, 15 column stops operatively mounted in said stop carrying member; denominational stops mounted upon said machine frame, numeral printing keys, letter printing keys, automatic means for positioning certain of said 20 stops, said automatic means including mechanisms adapted to be set and locked when one of the numeral keys is depressed, and means for unlocking said mechanisms when a letter key is depressed.

25 30. A device of the class described including a frame, a movable carriage mounted on said frame, stop members operatively connected with said movable carriage, stop members operatively connected with said 30 frame, printing keys comprising numeral keys, letter keys, punctuation keys, and automatic means for positioning certain of said stops, said automatic means including mechanisms adapted to be set and locked in 35 position when a numeral key is operated, means operatively connected with certain of said punctuation keys adapted to actuate said automatic means when said mechanisms are locked in operative position, and means 40 for releasing said mechanisms from locked position when a letter key is depressed.

31. A device of the class described including a frame, a movable carriage mounted on said frame, a stop member operatively 45 mounted on said frame, a stop member mounted on said movable carriage, means for automatically positioning one of said stop members, means for positioning the other stop member and releasing the movable carriage to permit said stops to contact, and means for disconnecting said means for automatically positioning one of said stop members in order to render said automatic means inoperative.

55 32. A device of the class described including a frame, a power propelled carriage mounted on said frame, a movable stop member mounted upon said frame, a movable stop member mounted upon said carriage, means for automatically positioning one of said stop members, means for positioning the other of said stop members and releasing the movable carriage to permit said stop members to contact, and discon-

necting means for rendering said automatically positioning means inoperative. 65

33. A device of the class described including a frame, a movable carriage mounted on said frame, a stop member operatively mounted on said frame, a series of stop members mounted on said movable carriage, means for automatically positioning certain of said stops in said series, means for positioning the stop member mounted on the frame and releasing the carriage to permit 75 the position of said carriage to be determined by contact of the stop mounted on the frame with stops which have been moved to operative position on the carriage frame, and disconnecting means for rendering said 80 automatically positioning means inoperative.

34. A device of the class described including a frame, a movable carriage mounted on said frame, a series of denominational stop members operatively mounted on said frame, a series of movable stops operatively connected with said carriage, means for automatically positioning certain of said series of stops, means for operating said denominational stops, and disconnecting means for rendering said automatically positioning means inoperative. 90

35. A device of the class described including a frame, a movable carriage mounted on said frame, a series of denominational stops operatively mounted on said frame, a stop carrying rack mounted on said movable carriage, stops carried by said stop carrying rack, means for automatically positioning 95 certain of said stops carried by said rack, means for positioning said denominational stops, and disconnecting means for rendering said automatically positioning means inoperative. 100

36. A device of the class described including a frame, a movable carriage, a stop member operatively connected with said movable carriage, a stop member operatively connected with said frame, automatic 110 means for positioning one of said stop members, means for positioning the other of said stop members in the path of said stop automatically positioned, and disconnecting means for rendering said automatic means 115 inoperative.

37. A device of the class described including a frame, a power propelled carriage, a stop member operatively connected with said power propelled carriage, a stop member operatively mounted upon said frame, automatic means for positioning certain of said stops carried by said carriage, means for positioning the stop member on said frame in the path of the positioned stop 120 members carried on the carriage, and disconnecting means for rendering said automatic means inoperative. 125

38. A device of the class described including a frame, a movable carriage, a series of column stop members normally in inoperative position, a series of denominational stop members, means for automatically positioning certain of said column stop members, means for positioning certain of said denominational stops in such manner as to be in the path of the positioned column stop members, and disconnecting means for rendering said automatically positioning means inoperative.

39. A device of the class described including a frame, a movable carriage, a series of column stop members operatively connected with said carriage and normally in inoperative position, a series of denominational stops operatively mounted upon said frame, means for automatically positioning certain of said column stops, means for positioning certain of said denominational stops in the path of the positioned column stops, and disconnecting means for rendering said automatically positioning means inoperative.

40. A device of the class described including a frame, a movable carriage mounted on said frame, a stop carrying rack operatively connected with said movable carriage, movable column stops mounted in said rack, denominational stops mounted upon said frame, means for automatically moving in said rack certain of said column stops from inoperative to operative position, means for positioning certain of said denominational stops in the path of said operative column stops, and disconnecting means for rendering said automatic means inoperative.

41. A device of the class described including a frame, keys operatively mounted in said frame, a movable carriage, a stop member operatively connected with said movable carriage and moving simultaneously therewith, a stop member mounted on said machine frame, means operatively connected with said keys adapted to set one of said stops in operative position when certain of said keys have been depressed in a pre-determined sequence, means for positioning the other of said stops in the path of the stop which was automatically set, and disconnecting means for rendering said first mentioned means inoperative.

42. A device of the class described including a frame, keys operatively mounted in said frame, a movable carriage, a series of stop members operatively connected with said movable carriage and moving simultaneously therewith, a series of stop members mounted upon said machine frame, means operatively connected with said keys adapted to set certain of said stops operatively connecting said carriage when certain of said keys have been depressed in a pre-determined sequence, means for positioning certain of said stops carried by the machine

frame in the path of the automatically positioned stops, and disconnecting means for rendering said first mentioned means inoperative.

43. A device of the class described including a frame, keys operatively mounted in said frame, a movable carriage, a stop carrying rack operatively connected with said carriage and moving simultaneously therewith, column stops movably mounted in said stop carrying rack, denominational stops mounted upon said machine frame, means operatively connected with said keys adapted to set certain of said column stops in operative position when certain of said keys have been depressed in a pre-determined sequence, means for positioning certain of said denominational stops in the path of said column stops, and disconnecting means for rendering said first mentioned means inoperative.

44. A device of the class described including a frame, keys operatively mounted in said frame, a movable carriage, a stop carrying rack, a series of column stops mounted in said stop carrying rack and normally in inoperative position, a series of denominational stops normally in inoperative position, means operatively connected with said keys adapted to set certain of said column stops in operative position when certain of said keys have been depressed in a pre-determined sequence, means for positioning certain of said denominational stops, means for releasing the carriage to permit said stops to contact, and disconnecting means for rendering said first mentioned means inoperative.

45. A device of the class described including a frame, keys operatively mounted on said frame, a movable carriage, stop members operatively connected with said movable carriage and moving simultaneously therewith, stop members mounted upon said machine frame, means operatively connected with said keys adapted to set certain of said stops in operative position when certain of said keys have been depressed in a pre-determined sequence, means for operatively positioning stops in the path of said first mentioned stops, means for releasing the carriage to permit said stops to contact, and disconnecting means for rendering said first mentioned stops inoperative.

46. A device of the class described including a frame, a movable carriage mounted upon said frame, printing means, finger keys operatively connected with said printing means, a stop carried by said movable carriage, a stop mounted upon said machine frame, means operatively connected with said finger keys for automatically setting one of said stops when said finger keys have been operated in a pre-determined sequence, means for positioning the other of

said stops in the path of said first mentioned stop, and disconnecting means for rendering said first mentioned means inoperative.

47. A device of the class described including a frame, a movable carriage mounted upon said frame, printing means, finger keys operatively connected with said printing means, a stop carrying member operatively connected with said movable carriage, stops carried by said stop carrying member, stops mounted upon said machine frame, means operatively connected with said finger keys for automatically setting certain of said stops on said stop carrying member in operative position when certain of said keys have been operated in a pre-determined sequence, means for positioning certain of said stops on said machine frame in the path of the operative stops carried by the carriage, and disconnecting means for rendering said first mentioned means inoperative.

48. A device of the class described including a frame, a movable carriage mounted upon said said frame, printing means, finger keys operatively connected with said printing means, a stop carrying rack operatively connected with said movable carriage, stops slidingly mounted in said stop carrying rack, a stop mounted on said machine frame, means operatively connected with said finger keys for automatically setting certain of said stops carried by said rack in the path of said stop mounted on said machine frame when certain keys have been depressed in a pre-determined sequence, and disconnecting means for rendering the automatic means for setting stops inoperative.

49. A device of the class described including a frame, a movable carriage mounted on said frame, printing means, finger keys operatively connected with said printing means, a stop carrying rack operatively connected with said movable carriage, a series of column stops mounted in said rack normally in inoperative position, a series of denominational stops mounted upon said machine frame, means operatively connected with said finger keys for automatically positioning certain of said denominational stops in operative position when said finger keys have been depressed in a pre-determined sequence, means for positioning certain of said denominational stops in the path of said operative column stops, and disconnecting means for rendering said first mentioned stops inoperative.

50. A device of the class described including a frame, a movable carriage mounted upon said frame, printing means, finger keys operatively connected with said printing means, a stop carrying rack, a series of column stops mounted in said stop carrying rack and normally in inoperative position,

a series of denominational stops normally in inoperative position, means operatively connected with said finger keys for automatically setting certain of said column stops in operative position when said finger keys have been operated in a pre-determined sequence, means for positioning certain of said denominational stops in operative position in the path of said operative column stops, means for releasing said carriage to permit said column and denominational stops to contact, and disconnecting means for rendering said first mentioned stops inoperative.

51. A device of the class described including a frame, a carriage movably mounted upon said frame, a stop carrier operatively connected with said carriage, stops mounted upon said stop carrier, printing mechanism, key levers operatively connected with said printing mechanism, a stop mounted on said frame, means for automatically rendering certain of said stops connected with said carriage operative to be engaged by said stops mounted on said machine frame when a punctuation key is operated in immediate sequence after a numeral key, and disconnecting means for rendering said automatic means inoperative.

52. A device of the class described including a frame, a carriage movably mounted on said frame, a stop carried by said carriage, a stop operatively mounted upon said frame, printing mechanisms, key levers operatively connected with said printing mechanisms, means for automatically setting one of said stops when a punctuation key is operated immediately after a numeral key, means for positioning the other stop in the path of said first mentioned stop, and disconnecting means for rendering said automatic setting means inoperative.

53. A device of the class described including a frame, a carriage movably mounted upon said frame, a stop carrying rack operatively connected with said carriage and adapted to move simultaneously therewith, stops mounted upon said rack, printing mechanisms, key levers operatively connected with said printing mechanisms, stops mounted upon said frame, means for automatically setting certain of said stops on said stop carrier in operative position when a punctuation key is operated in immediate sequence after a numeral key, means for positioning certain of said stops mounted on said frame in the path of said operative stops carried by said rack, and disconnecting means for rendering said automatic means inoperative.

54. A device of the class described including a frame, a carriage movably mounted upon said frame, a stop carrying rack, a series of column stops movably mounted in said stop carrying rack, printing mechan-

isms, key levers operatively connected with said printing mechanisms, a series of denominational stops, means for automatically setting certain of said column stops when a punctuation key is operated in immediate sequence after a numeral key, means for positioning certain of said denominational stops in the path of the column stops which have been automatically set, and disconnecting means for rendering said automatic means inoperative.

55. A device of the class described including a frame, a carriage movably mounted upon said frame, a stop carrying rack mounted upon said carriage, a series of column stops mounted on said rack, printing mechanisms, key levers operatively connected with said printing mechanisms, denominational stops mounted on said frame, means 20 for automatically setting certain of said column stops when a punctuation key is operated in immediate sequence after a numeral key, means for positioning certain of said denominational stops in the path of said operative column stops, and disconnecting means for rendering said automatic means inoperative.

56. A typewriting machine including a movable carriage, printing mechanism, finger keys operatively connected with said printing mechanism, a tabulating device including column stops, denominational stops, means for automatically setting certain of said column stops when certain of said finger keys are operated in a predetermined sequence, and disconnecting means for rendering said automatic means inoperative.

57. A device of the class described including a frame, a movable carriage mounted on said frame, a stop carrying member operatively connected with said movable carriage, a stop member operatively connected with said frame, key levers, automatic means for positioning certain of said stops, said 45 automatic means including mechanisms for rendering said automatic means operative when certain of said keys are depressed, means for rendering said automatic mechanisms inoperative when certain other of 50 said keys are depressed, and disconnecting means for rendering said automatic means inoperative with relation to any of said printing keys.

58. A device of the class described including a frame, a movable carriage mounted on said frame, a stop carrying member operatively connected with said movable carriage, stops carried by said stop carrying member, key levers, automatic means for positioning certain of said stop members, said 60 automatic means including mechanisms adapted to be set and locked in position to render said automatic means operative when certain of said printing keys are depressed,

and disconnecting means for rendering said 65 automatic means inoperative.

59. A device of the class described including a frame, a movable carriage mounted on said frame, a stop carrying member operatively connected with said movable carriage, 70 column stops operatively mounted in said stop carrying member, denominational stops mounted upon said machine frame, numeral printing keys, letter printing keys, automatic means for positioning certain of said 75 stops, said automatic means comprising mechanisms adapted to be set and locked when one of the numeral keys is depressed, means for unlocking said automatic means when a letter key is depressed, and disconnecting means for rendering said automatic 80 means inoperative.

60. A device of the class described including a frame, a movable carriage mounted upon said frame, stop members operatively connected with said movable carriage, stop members operatively connected with said frame, printing keys comprising numeral keys, letter keys, punctuation keys, and automatic means for positioning certain of 90 said stops, said automatic means comprising mechanisms adapted to be set and locked in position when a numeral key is operated, means operatively connected with certain of said punctuation keys adapted to actuate 95 said automatic means when said mechanisms are locked in operative position, means for releasing said mechanisms from locked position when a letter key is depressed, and disconnecting means for rendering said 100 automatic means inoperative.

61. In a device of the class described in combination, a frame, a movable carriage mounted upon said frame, stops operatively connected with said movable carriage, stops 105 operatively mounted upon said machine frame, printing keys, automatic means for setting certain of said stops including mechanisms for rendering said automatic means operative when certain of said printing keys are depressed, means for actuating said automatic means when certain other of 110 said printing keys are depressed, and disconnecting means for rendering said automatic means inoperative.

62. A device of the class described including a frame, a movable carriage mounted on said frame, a stop member operatively mounted on said frame, a stop member mounted on said movable carriage, means 120 for automatically positioning one of said stop members, means for locking in set position said stop which has been automatically positioned, and means for positioning the other stop member and releasing the movable carriage to permit said stops to contact.

63. A device of the class described including a frame, a power propelled carriage

mounted on said frame, a movable stop member mounted upon said frame, a movable stop member mounted upon said carriage, means for automatically positioning 5 one of said stop members, means for locking in set position said stop which has been automatically positioned, and means for positioning the other of said stop members and releasing the movable carriage to permit 10 said stop members to contact.

64. A device of the class described including a frame, a movable carriage mounted on said frame, a stop member operatively mounted on said frame, a series of stop 15 members mounted on said movable carriage, means for automatically positioning certain of said stops in said series, means for locking in set position said stops which have been automatically positioned, and means 20 for positioning the stop member mounted on the frame and releasing the carriage to permit the position of said carriage to be determined by contact of the stop mounted on the frame with stops which have been 25 moved to operative position on the carriage frame.

65. A device of the class described including a frame, a movable carriage mounted on said frame, a series of denominational stop 30 members operatively mounted on said frame, a series of movable stops operatively connected with said carriage, means for automatically positioning certain of said series of stops, means for locking in set position 35 said stops which have been automatically positioned, and means for operating said denominational stops.

66. A device of the class described including a frame, a movable carriage mounted on 40 said frame, a series of denominational stops operatively mounted on said frame, a stop carrying rack mounted on said movable carriage, stops carried by said stop carrying rack, means for automatically positioning 45 certain of said stops carried by said rack, means for locking in set position said stops which have been automatically positioned, and means for positioning said denominational stops.

67. A device of the class described including a frame, a movable carriage, a stop member operatively connected with said movable carriage, a stop member operatively connected with said frame, automatic means 55 for positioning one of said stop members, means for locking in set position said stop which is positioned by said automatic means, and means for positioning the other of said stop members in the path of said stop automatically positioned.

68. A device of the class described including a frame, a power propelled carriage, stop members operatively connected with said power propelled carriage, a stop member 65 operatively mounted upon said frame,

automatic means for positioning certain of said stops carried by said carriage, means for locking in set position said stops which are positioned by said automatic means, and means for positioning the stop member on 70 said frame in the path of the positioned stop members carried on the carriage.

69. A device of the class described including a frame, a movable carriage, a series of column stop members normally in inoperative 75 position, a series of denominational stop members, means for automatically positioning certain of said column stop members, means for locking said column stop members against retrograde movement, and means for positioning certain of said denominational stops in such manner as to be 80 in the path of the positioned column stop members.

70. A device of the class described including a frame, a movable carriage, a series of column stop members operatively connected with said carriage and normally in inoperative position, a series of denominational stops operatively mounted upon said frame, 90 means for automatically positioning certain of said column stops, means for locking said column stops against retrograde movement, and means for positioning certain of said denominational stops in the path of the positioned column stops. 95

71. A device of the class described including a frame, a movable carriage mounted on said frame, a stop carrying rack operatively connected with said movable carriage, movable column stops mounted in said rack, denominational stops mounted upon said frame, means for automatically moving in said rack certain of said column stops from inoperative to operative position, means for 100 locking said column stops against retrograde movement, and means for positioning certain of said denominational stops in the path of said operative column stops.

72. A tabulating device including a stop carrying rack, a series of column stops movably mounted in said rack, mechanism for locking said stops in an operative position, abutment members on said column stops, a retractor bar adapted to coöperate 115 with said abutment members to return to normal position any of said stops which have been set in operative position, and means for releasing said set stops from the locking mechanism and actuating the retractor bar.

73. A tabulating device including a stop carrier, column stops movably mounted in said stop carrier, means for locking said stops against retrograde movement, said 120 means being operable to unlock all of said stops, and means in the carrier for moving any of said stops which have been set in operative position to normal position.

74. A tabulating device including a stop 130

carrier; a series of column stops mounted in said stop carrier, means in the carrier for locking said column stops in both normal and operative positions, means for unlocking said stops, and means for moving any of said stops which have been set from set position to normal position.

75. A tabulating device including a stop carrying rack, column stops carried by said rack, said column stops being adapted to be set from normal to operative position, means for locking said column stops, means for unlocking said column stops, and means for positioning simultaneously any of said 10 column stops from operative position to normal position.

76. A tabulating device including a stop carrying rack, column stops mounted in said rack, said column stops being adapted to be 20 set from normal to operative position, means for locking said column stops, and means for simultaneously unlocking and returning said column stops from set position to normal position.

77. A tabulating device including a stop carrying rack, movable stops mounted in said rack, said movable stops comprising a stop face, a spring member provided with locking notches, and a side member 30 provided with an abutment.

78. A device of the class described, including a frame, a movable carriage mounted on said frame, a stop member operatively mounted on said frame, a stop member 35 mounted on said movable carriage, means for automatically positioning one of said stop members, said automatic means including mechanism adapted for a limited movement in the direction of the movement of 40 said carriage, and means for positioning the other stop member and releasing the movable carriage to permit said stops to contact.

79. A device of the class described, including a frame, a movable carriage mounted on said frame, a stop member operatively connected with said carriage, a stop member mounted upon said frame, automatic means for positioning one of said stop members, said automatic means including a mechanism adapted to have a limited movement in the direction of the movement of said carriage, and means for positioning the other of said stop members and releasing the movable carriage to permit said stop members to contact.

80. A typewriting machine including a frame, a movable carriage mounted on said frame, a stop carrying member operatively connected with said movable carriage, stops 60 carried in said stop carrying member, and automatic means for positioning certain of said stops, said automatic means including mechanism adapted for a limited movement in the direction of movement of said carriage.

81. In a device of the character described in combination; a frame; a movable carriage mounted upon said frame; stops operatively connected with said movable carriage; stops operatively mounted upon said machine 70 frame; printing keys; automatic means for positioning certain of said stops, said automatic means including mechanisms for rendering the positioning means operative when certain of said printing keys have been depressed; and means for actuating said positioning means when certain other of said printing keys are depressed.

82. In a typewriting machine in combination, a traveling carriage, type members including punctuation characters and numeral characters, mechanism including keys for operating said type members to print the characters thereon, tabulator stops carried by said traveling carriage, and means for setting one of said stops when a punctuation character is printed after a numeral character.

83. In a typewriting machine in combination, a traveling carriage, a tabulator stop, 90 means capable of co-operating with said tabulator stop to control the movement of said carriage when said tabulator stop has been set, and mechanism operating to simultaneously set the tabulator stop and print a 95 character.

84. In a typewriting machine in combination, a traveling carriage, a tabulator stop, mechanism operative to limit the movement of said carriage when said tabulator stop 100 has been set, a key performing an operative function in connection with the operation of said machine, and means operatively connected with said key to enable said key to perform its normal function and simultaneously set said tabulator stop.

85. In a device of the character described, a traveling carriage, a tabulator stop capable of limiting the movement of said carriage when said stop is operated, a key board 110 comprising a plurality of keys capable of performing definite functions, and a key in said key board performing its normal function and simultaneously rendering said tabulator stop capable of being operative to limit the movement of said carriage.

86. In a device of the character described, a traveling carriage, a tabulator stop for controlling the movement of said carriage, a key board comprising a plurality of keys, a 120 key in said key board operable to set said stop when certain other keys are operated in a predetermined sequence.

87. In a typewriting machine in combination, a machine frame, a traveling carriage, 125 a plurality of tabulator stops, and means for setting said tabulator stops, said means being capable of movement with said carriage.

88. In a device of the character described in combination, a machine frame, a traveling 130

carriage, a plurality of tabulator stops comprising a series, and means for setting certain of the stops in said series from inoperative to operative position, said means being capable of travel coördinately with the movement of said carriage.

89. In a device of the character described in combination, a machine frame, a traveling carriage, a plurality of tabulator stops arranged in series, a key mounted upon said

frame, and means operatively connected with said key for setting certain of said stops from inoperative to operative position, said means being capable of movement simultaneous and coincident with the movement of said carriage.

GEORGE W. RAMSEY.
